UNITED STATES PATENT OFFICE.

SYDNEY B. GRIFFIN, OF MAMARONECK, NEW YORK.

DISPLAY DEVICE.

1,390,700.

Specification of Letters Patent. Patented Sept. 13, 1921.

Application filed November 24, 1920. Serial No. 426,119.

To all whom it may concern:

Be it known that I, SYDNEY B. GRIFFIN, a citizen of the United States, residing at Mamaroneck, in the county of Westchester 5 and State of New York, have invented certain new and useful Improvements in Display Devices, fully described and represented in the following specification and the accompanying drawing, forming a part of 10 the same.

This invention relates to display devices and has for an object the providing of means for retaining a poster or the like flat and erect while permitting the poster to be 15 rolled into a small package for ease in transportation.

According to my invention, the poster is mounted or printed upon flexible material, such as paper or cloth. Two edge pieces 20 are attached along the back of opposite parallel edges of the poster and these edge pieces are provided with correspondingly placed hinges which permit their ends to bend in planes perpendicular to the edges 25 of the poster to which they are attached. Thrust pieces are provided for pressing apart the edge pieces to stretch the poster flat, while the bending of the edge pieces permitted by the hinges allows the stretched 30 poster to be bent into such position that it will stand erect without outside support. The thrust pieces are so arranged that they may be folded upon one of the edge pieces and when so folded serve to prevent this 35 edge piece from bending so that the folded thrust pieces and the edge piece form a straight rigid bar upon which the poster may be rolled for ease in transportation.

My invention will be fully understood 40 from a detailed description of the embodiment of it illustrated in the accompanying drawing in which:—

Figure 1 is a top view of the device in display position;

Fig. 2 is a back elevation of the device in display position;

Fig. 3 is a top view showing the thrust pieces folded preparatory to rolling the poster for transportation;

Fig. 4 is a fragmentary perspective view showing the construction of the hinges of the edge pieces; and

Fig. 5 is a fragmentary sectional plan view of one of the hinges.

The poster 10 comprises a piece of flexible material such as cloth or paper upon one

side of which display matter is printed, or otherwise displayed. Along the rear side of opposite edges of the poster 10 are attached jointed edge pieces 11, 12. The edge piece 60 11 comprises a middle member 13 and two end members 14, 15, which are hinged to the ends of the middle member 13 in such a way that they may swing forward in a plane perpendicular to the edge of the poster 10 to which the edge piece 11 is attached. The edge piece 12 comprises a middle member 16 and two end members 17 and 18 hinged to it so as to swing forward in a plane parallel to the edge of the poster 70 10 to which the edge piece 12 is attached. The hinges of the edge piece 12 are directly below the hinges of the edge piece 11. The material of the poster 10 is creased or scored along the line connecting opposite hinges to 75 facilitate its bending on that line.

The construction of the hinges of the edge pieces is illustrated in Fig. 4. Each hinge comprises a tongue 20 upon the end of one of the members adapted to fit within a 80 recess 21 in the end of the adjacent member. The members are connected by a pivot pin 22. The front faces of each of the members are cut away at 23 to provide a space in which the bulge of the material of the poster 85 10 between the edge members may lie when the edge members are bent at an angle to each other. When the edge members are extended straight the end of the tongue 20 of one member engages the end of the recess 21 of the adjacent member (Fig. 5) so that backward bending of the hinge, which would result in tearing the material of the poster 10, is prevented.

The thrust piece 25 comprises two thrust 95 members 26 and 27, whose inner ends are overlapped and connected together by a pivot 28. The outer end of the thrust member 26 is connected to the middle of the back of the end member 14 of the edge piece 11 by 100 a pivot 29. The outer end of the thrust member 27 is provided with a projection 30 adapted to engage a socket 31 in the inner edge of the end member 17 of the edge piece 12. The thrust member 32 is similar to the thrust member 25. Its upper end is attached to the middle of the end member 15 of the edge piece 11 by a pivot 33, while its lower end is adapted to engage a socket 34 in the end member 18 of the edge piece 12. 105

The operation of the device described is as follows:—When the poster 10 is to be 110

displayed, it is unrolled and the thrust pieces 25, 32 are extended nearly straight across the back of the poster 10. Their free ends are then inserted in the sockets 5 31, 34, and the pivot point of each thrust member is moved sidewise to cause the thrust member to extend in a straight line. When so extended, the thrust member 25 exerts an outward thrust between the end 10 members 14 and 17 and the thrust member 32 exerts an outward thrust between the end members 15 and 18. This draws tight the portions of the poster 10 between the end pieces. As the jointed edge pieces cannot 15 bend except in a plane perpendicular to the edges of the poster 10, the outward thrust upon the end members of the edge pieces serves also to draw the middle members 13, 16 of the edge pieces outwardly and so 20 stretches the middle of the poster 10 tight.

After the entire poster is drawn flat by the placing of the thrust pieces as described, the end members of the edge pieces and the 25 portions of the poster between them may be bent forward as shown in Fig. 1 so as to enable the poster to stand erect without outside support. In such bending the material of the poster bends along the line of the creases or scores connecting the opposite 30 hinges so that the portion of the poster between the middle members of the edge pieces and the portions between the end members of the edge pieces remain flat.

When it is desired to transport the device, 35 the end members of the edge pieces are swung upon their hinges until they extend in a line with the middle members of the edge pieces. The thrust pieces 25, 32 are then bent sidewise, disengaged from the 40 sockets 31, 34, and folded against the edge piece 11. In folding the thrust pieces, the thrust members which are pivoted to the end members are extended outwardly along the end members, while the lower thrust 45 members are extended inwardly so that their free ends overlap behind the middle member 13 as shown in Fig. 3. The poster 10 is then rolled tightly around the edge piece 11, and the folded thrust pieces. The first turn of 50 the poster about the edge piece 11 and the folded thrust pieces retains the free ends of the thrust pieces against the middle member 13 of the edge piece 11 and thus retains the end members 14, 15, of the edge piece in 55 line with the middle member 11 so that a straight rigid bar is provided upon which the poster may easily be rolled.

Many modifications may be made in the embodiment described without departing from 60 the invention. Thus, while the foldable thrust pieces described have the peculiar advantages pointed out above, any desired means for thrusting apart the opposite members of the edge pieces may be provided 65 without departing from the scope of the in-

vention in its broader aspect. If desired, the number of hinges in each edge piece may be increased or decreased. The device may be used for the display of pictures, photographs and printed matter of all kinds, all 70 of which are intended to be included in the term "poster" in the claims following.

What is claimed is:

1. The combination with a flexible poster having parallel opposite edges, of edge 75 pieces secured along said opposite edges of the poster and each comprising an intermediate member and two end members hinged to the ends of the intermediate member so as to swing in a plane perpendicular to the 80 ends of the poster, the hinges of one edge piece being opposite the hinges of the other edge piece, and means for thrusting apart corresponding end members of the two edge pieces and thereby drawing apart the intermediate members of the edge pieces so that the whole poster is drawn tight.

2. The combination with a flexible poster having parallel opposite edges, of edge 90 pieces secured along said opposite edges of the poster and each comprising an intermediate member and two end members hinged to the ends of the intermediate member so as to swing in a plane perpendicular to the 95 ends of the poster, the hinges of one edge piece being opposite the hinges of the other edge piece and the material of the poster being formed to bend along the lines connecting the opposite hinges, and means for thrusting apart corresponding end members 100 of the two edge pieces and thereby drawing apart the intermediate members of the edge pieces so that the whole poster is drawn tight.

3. The combination with a flexible poster 105 having parallel opposite edges, of edge pieces secured along said opposite edges of the poster and each comprising an intermediate member and two end members hinged to the ends of the intermediate member so as to swing in a plane perpendicular to the 110 ends of the poster, the hinges of one edge piece being opposite the hinges of the other edge piece, and foldable thrust pieces adapted to thrust apart corresponding end 115 members of the two edge pieces and thereby draw apart the intermediate members of the edge pieces so that the whole poster is drawn tight.

4. The combination with a flexible poster 120 having parallel opposite edges, of edge pieces secured along said opposite edges of the poster and each comprising an intermediate member and two end members hinged to the ends of the intermediate member so as to swing in a plane perpendicular to the 125 ends of the poster, the hinges of one edge piece being opposite the hinges of the other edge piece and the poster being creased along the line connecting opposite hinges, 130

and foldable thrust pieces adapted to thrust apart corresponding end members of the two edge pieces and thereby draw apart the intermediate members of the edge pieces so 5 that the whole poster is drawn tight.

5. The combination with a flexible poster having parallel opposite edges, of edge pieces secured along said opposite edges of the poster and each comprising an intermediate member and two end members hinged to the ends of the intermediate member so as to swing in a plane perpendicular to the ends of the poster, the hinges of one edge piece being opposite the hinges of the other 10 edge piece, and foldable thrust pieces adapted to thrust apart corresponding end members of the two edge pieces and thereby draw apart the intermediate members of the edge pieces so that the whole poster is drawn 15 tight, each of said thrust pieces being permanently pivoted to an end member of one of the edge pieces.

6. The combination with a flexible poster having parallel opposite edges, of edge pieces secured along said opposite edges of the poster and each comprising an intermediate member and two end members hinged to the ends of the intermediate member so as to swing in a plane perpendicular 20 to the ends of the poster, the hinges of one edge piece being opposite the hinges of the other edge piece, two thrust pieces each adapted to exert an outward thrust upon corresponding end members of said 25 edge pieces and each comprising a thrust member pivoted to one of the end members of one of said edge pieces, and a thrust member pivoted to said first mentioned thrust member and having its free 30 end adapted to engage one of the end members of the other of said edge pieces, said thrust members being adapted to fold against the one of said edge pieces to which they are pivoted with their free ends over- 35 lapping.

7. In a display device, the combination with a flexible poster, of a piece secured

along the back of the poster and comprising members hinged together and each having its front side cut away at the end adjacent 50 to the hinge to provide a space for the bulge of said poster when said members are bent forwardly on their hinge.

8. In a display device, the combination with a flexible poster, of a piece secured 55 along the back of the poster and comprising members having their adjacent ends pivotally connected together, one of said ends being provided with a recess and the other with a tongue adapted to engage the end 60 of the recess when the piece lies in a straight line and thus prevent a backward bending of the piece.

9. In a display device, the combination with a flexible poster, of a piece secured 65 along the back of the poster and comprising members connected together by a hinge arranged to prevent backward bending of the piece while permitting it to bend forwardly, and having a groove to provide a space for 70 the bulge of said poster when the piece is bent forwardly.

10. The combination with a flexible poster having parallel opposite edges, of edge pieces secured along said opposite edges of 75 the poster and each comprising members hinged together so as to swing in a plane perpendicular to the ends of the poster, the hinge of one edge piece being opposite the hinge of the other edge piece, and means for 80 thrusting apart corresponding members of the edge pieces and thereby holding the poster flat while permitting the portions of the poster upon opposite sides of the line connecting said hinges to be bent at an angle 85 to each other so that the poster will stand erect.

In testimony whereof I have hereunto set my hand in the presence of two subscribing witnesses.

SYDNEY B. GRIFFIN.

Correction in Letters Patent No. 1,390,700.

It is hereby certified that Letters Patent No. 1,390,700, granted September 13, 1921, upon the application of Sydney B. Griffin, of Mamaroneck, New York, for an improvement in "Display Devices," were erroneously issued to the inventor, said Griffin, as owner of said invention, whereas said Letters Patent should have been issued to *T. Fred Moore, of New York, N. Y.*, as assignee of the *entire interest* in said invention, as shown by the record of assignments in this office; and that the said Letters Patent should be read with this correction therein that the same may conform to the record of the case in the Patent Office.

Signed and sealed this 15th day of November, A. D., 1921

[SEAL.]

KARL FENNING,

Acting Commissioner of Patents.
